UNITED STATES PATENT OFFICE

CARL W. PIERSON, OF ROCKFORD, ILLINOIS

DESIGN FOR A RADIO RECEIVING SET

Application filed September 28, 1931. Serial No. 41,249. Term of patent 7 years.

To all whom it may concern:

Be it known that I, CARL W. PIERSON, a citizen of the United States, residing at Rockford, in the county of Winnebago and State of Illinois, have invented a new, original, and ornamental Design for a Radio Receiving Set, of which the following is a specification, reference being had to the accompanying drawings, forming part hereof.

Figure 1 of the drawings is a front elevational view of a radio receiving set embodying the new design. Fig. 2 is an elevational view of one of the side panels. Fig. 3 is a plan view.

The design is especially adapted to fit snugly into the corner of a room and is characterized by the use of a cabinet or casing of generally pentagonal cross-sectional shape having a front wall composed of two side faces or panels, and an intermediate panel, the adjacent panels being disposed at angles of less than 90 degrees relative to each other.

I claim:

The ornamental design for a radio receiving set, substantially as shown and described.

CARL W. PIERSON.
